(57) **CLAIM**

The ornamental design for a display screen or portion thereof with graphical user interface, as shown and described.

DESCRIPTION

The FIGURE is a front view of a display screen or portion thereof with graphical user interface, showing our new design.

The outer perimeter broken lines in the FIGURE depict a display screen or portion thereof and form no part of the claimed design. The remainder of the broken lines in the FIGURE depicts portions of the graphical user interface that form no part of the claimed design. The contrast shown in grayscale in the claimed portion of the FIGURE represents a contrast of appearance.
